TOP LIFT FOR SHOE HEELS

John E. Aeh, Portsmouth, Ohio

Application June 23, 1939, Serial No. 280,870

2 Claims. (CL. 36—42)

This invention relates to a lift for shoe heels. An object of the invention is the provision of a device for easily snapping into place a lift for shoe heels in which the lift will be rigidly held in position against displacement and in which the elements connecting the lift to the bottom of the heel will be entirely enclosed within the heel and lift so that the connecting elements when the lift is applied will not appear at any point on the surface of the heel or the lift.

Another object of the invention is the provision of a lift which may be readily applied or removed from a heel when desired in which a pair of separable fasteners are employed for connecting the lift to the heel so that when it is necessary to substitute a new lift for an old one the lift may be purchased with the connector or fastener already attached and applied to the heel after the old one has been removed.

A further object of the invention is the provision of a heel and a readily removable lift in which a metallic member is embedded in a countersunk portion of the bottom of the heel so that the outer face of the metallic member will be flush with the outer surface of the bottom of the heel, said metallic member being endless and having a tongue projecting inwardly with the free end of the tongue being reduced to be received by a notched end of a second member secured upon the inner face of the heel lift, the endless member opposite the tongue being provided with a notch to receive prongs projecting from the opposite ends of the member applied to the lift, the construction being such that when the heel lift is locked in place the connecting member on the heel lift will be received within the center of the endless member so that no parts of the two connecting members will appear at the surface of the heel.

This invention will be best understood from a consideration of the following detailed description, in view of the accompanying drawing forming a part of the specification; nevertheless, it is to be understood that the invention is not confined to the disclosure, being susceptible of such changes and modifications as define no material departure from the salient features of the invention as expressed in the appended claims.

In the drawing:

Figure 1 is a view in perspective looking towards the bottom of a heel which may be formed of wood or any composition material showing a connecting plate countersunk in the bottom of the heel.

Figure 2 is a view in perspective of a lift having a cooperating connecting member applied to the inner surface thereof.

Figure 3 is a side view of the heel partly in section showing the lift removably connected to the bottom of the heel.

Figure 4 is an enlarged bottom plan view of the heel with a connecting countersunk into the said heel.

Figure 5 is a plan view of the lift and its connecting member.

Figure 6 is a view in perspective of the connecting member which is applied to the bottom of the heel.

Figure 7 is a view in perspective of the connecting member applied to the lift, and

Figure 8 is a fragmentary enlarged vertical section showing the connecting members in operative relation for attaching a lift to the bottom of a heel.

Referring more particularly to the drawing, 20 10 designates a heel which is formed of wood, leather or some composition material and to which is adapted to be attached a lift 11 formed of any suitable material which may be leather or rubber. The lift is ordinarily nailed or cemented to the bottom face 12 of the heel.

A metal connecting plate, generally designated by the numeral 13, is connected by nails or other suitable securing means 14 in a pocket or countersunk portion 15 formed in the bottom of the heel as shown more particularly in Figs. 3 and 8.

The plate consists of an annular metallic member which is substantially semi-circular, as shown at 16, with a bar 17 connecting the ends of the semi-circular member. The bar and the semi-circular member are formed in one piece.

Intermediate the ends of the semi-circular member is provided a notch 20 from which projects a sharp pointed tongue 21 and this tongue terminates short of the inner periphery of the semi-circular portion 16 and projects inwardly towards the bar 17.

The bar (Fig. 6) is provided with a pair of slots 22 which are cut through the upper surface of the plate, leaving thin strips 23 of metal 45 at the outer surface of the bar for a purpose which will be presently explained so that when the member 13 is seated within the pocket 15 in the heel 10 and is secured thereto the strips 23 in connection with the bottom of the countersunk portion 15 will form a pair of pockets.

A U-shaped connecting member generally designated by the numeral 25, is provided with perforations 26 through which are inserted tacks, nails or other suitable securing means for at-

55

taching the U-shaped member to the inner face of the lift 11. A finger 27 projects from the bight portion 28 of the U-shaped member and the free end is provided with a notch 29 to receive the reduced or sharpened end 21 of the tongue 20. It will be noted from Fig. 7 that the edges 30 at each side of the notch 29 are rounded to facilitate the snapping of the finger 27 into position on the tongue 21. The outer free ends of the legs 31 are cut away to provide prongs 32 which are received within the pockets or slots 22 in the bar 17 of the member 13 and these prongs are made sufficiently thin so that when the member 25 is forced into place there will be sufficient resilience to permit the member 25 to be tightly fitted in position within the open space 33 formed in the endless member 13.

The member 25 is of the same thickness or slightly thinner than member 13 so that when the lift 11 is snapped into position on the outer face 12 of the heel 10, the inner face of the lift 11 will be in snug relation with the outer face 12 of the heel 10.

When the member 13 is placed in the position shown in Fig. 1, then the connector 25 is secured to the inner face of the lift 11 and it is only necessary to position the lift on the bottom of the heel so that the prongs 32 will be received within the slots 22 of the bar 17 of the member 13. The lift will then be tilted outwardly from the bottom of the heel adjacent the breast 34 of the heel. The inner end of the lift is then moved towards the bottom of the heel and when sufficient pressure is applied the rounded edge 30 at one side of the notch 29 on the tongue 27 will be forced over the reduced end 21 of the tongue 20 and the lift will not only be secured in place against displacement but due to the fact that the prongs 32 are snugly fitted between the bottom face 12 of the heel 10 and the strip 23 and also due to the fact that the tongue 20 being received within the notch 29 of the finger 27, the lift will snugly engage the bottom face of the heel and will be securely held in place against displacement during walking.

As has been stated, when it is necessary to ap-

ply a new lift to the heel, the worn lift is forced away from the heel at the back and then removed. The connecting means 25 may be removed from the old lift and applied to a new lift and returned to locked position on the bottom of the heel. Ordinarily the connecting members 25 are attached to the lifts so that it is only necessary to remove the old lift and apply a new one and a new connector to the heel. As has been stated, the connector 25 may be removed and supplied to other lifts so that the connector may be used a number of times.

I claim:

1. A detachable heel for shoes comprising a metallic keeper including a substantially semi-circular member and a cross bar connecting the ends of the member, said member intermediate the ends thereof having a notched portion, a sharp edged tongue located in the notched portion, said bar having spaced slots, means securing the keeper in a countersunk portion of the heel, a heel lift, a U-shaped member secured to the inner face of the lift and having prongs projecting from the ends of the legs and received by the slots in the bar, a finger projecting from the bight portion of the U-shaped member and provided with a notch at the free end to receive the sharp-edged tongue for locking the lift to the heel.

2. A detachable heel for shoes comprising a keeper including an endless member provided with an inwardly projecting tongue having a reduced free end, said member opposite the tongue being provided with a slot, means securing the keeper in a countersunk portion of the heel, a heel lift, a connecting member secured to the inner face of the heel lift and adapted to be received by the endless member, a prong projecting from one end of the connecting member and received by the slot, a finger projecting from the opposite end of the connecting member and provided with a notch at the free end adapted to receive the reduced free end of the tongue when the finger is forced over the tongue.

JOHN E. AEH.
